UNITED STATES PATENT OFFICE.

DAVID COCHRAN, OF RICHTON, MISSISSIPPI.

PLOW.

1,082,406.

Specification of Letters Patent.

Patented Dec. 23, 1913.

Application filed April 23, 1913. Serial No. 763,097.

To all whom it may concern:

Be it known that I, DAVID COCHRAN, a citizen of the United States, residing at Richton, in the county of Perry and State 5 of Mississippi, have invented new and useful Improvements in Plows, of which the following is a specification.

This invention relates to plows of that class which are generally known as hillside 10 plows and which are equipped with a pivotally and reversibly supported member constituting a double share having right and left hand mold boards.

The present invention has for its object 15 to simplify and improve the construction and operation of this class of devices and to furnish an implement which may be constructed at a small expense.

A further object of the invention is to so 20 construct the improved plow that the reversible share may be applied to and used in connection with a bifurcated standard of ordinary construction, such as is used in connection with scrapers, scooters and the like.

25 A further object of the invention is to produce an implement of the class described including a spring which assists in reversing the share to present a right hand or a left hand plow, as may be required.

30 With these and other ends in view which will readily appear as the nature of the invention is better understood, the same consist in the improved construction and novel arrangement and combination of parts which 35 will hereinafter be fully described and particularly pointed out in the claims.

In the accompanying drawing has been 40 illustrated a simple and preferred form of the invention, it being, however, understood that no limitation is necessarily made to the precise structural details therein exhibited, but that changes, alterations and modifications within the scope of the claims may be resorted to when desired.

45 In the drawing, Figure 1 is a perspective view of a plow constructed in accordance with the invention. Fig. 2 is a rear view, showing the plow in the act of being turned or reversed. Fig. 3 is a side elevation taken 50 from the side opposite to that shown in Fig. 1.

Corresponding parts in the several figures are denoted by like characters of reference.

The plow beam 1 having the handles 2 and the standard 3 may be of any preferred 55 type, the standard being preferably bifur-

cated and provided at its lower end with a block or foot piece 4; said standard being also connected with the rear end of the beam by a suitable brace 5. The reversible share 6 A, which is connected with the standard by a bolt or pivot member 14, preferably consists of an integral web presenting points 6 and mold boards 7 of any desired shape, 65 said plows and mold boards at the two ends 65 of the reversible share being, respectively, of the right and the left hand type, although in some instances an ordinary turning plow may be formed at one end and a sub-soiler at the other end of the share, or 70 the construction may be otherwise varied. By reason of the share being formed of an integral web which is not cut out or slotted intermediate the wings of the mold boards, the said implement will shed the dirt in a 75 more satisfactory manner, and the implement will be found much less liable to clog than were the wings of the mold board struck out from the metallic web. The point 8 where the tips of the mold boards 80 converge is provided with an attaching member, such as an eye bolt 9 that extends rearwardly in parallel relation to the axis of the bolt or pivot member 14, and the purpose of which will be presently made apparent. 85

Fulcrumed on one side face of the beam near the rear end of the latter is a lever 10 which normally lies beneath one of the handles and which is provided at the end of one 90 of its arms with a handle 11, whereby it may be manipulated. The other arm of the lever is provided with a spur 12 which is guided through the bifurcated standard and which is adapted to engage one of the apertures 13 95 formed in the share 7 at diametrically opposite sides of the axis of the bolt or pivot member 14, whereby said share is pivoted on the block or foot piece 4. By means of the spur 12 the reversible share may be securely 100 retained in position for operation with either the right hand plow or the left hand plow presented downwardly for use.

The eye bolt or attaching member 9 at the convergence of the right and left hand mold 105 boards is connected by means of a coiled spring 15 with the rear end of the beam 1 where a bracket member 16 may be provided for the attachment of the upper end of the spring. The lever 10 is actuated by 110 means of an independent spring 17 interposed between said lever and one of the plow

handles, and whereby the spur 12 of said lever will be maintained in engagement with one of the apertures 13, as will be readily understood, and as clearly seen in Fig. 1 of the drawings.

When it is desired to reverse the plow, the handle of the lever is manipulated to move said lever against the tension of the spring 17 sufficiently to disengage the spur 12 from the aperture 13. The plow share is then tilted to the position shown in Fig. 2, this tilting being readily effected by the gravity of the plow beam and standard which will operate against the tension of the spring 15 which is thereby tensioned as the convergence of the mold boards passes beneath the lower end of the standard. When a dead center has been passed the tension of the spring will be exerted to assist in restoring the reversible share to an operative position, the operation of reversing the share being thus accomplished very easily and with little manual strain on the part of the operator. By reason of the rearwardly extending eye bolt 9, the lower end of the spring will be sufficiently spaced from the standard to clear the latter without interference while the reversal is being accomplished.

Having thus described the invention, what is claimed as new, is:—

1. In a plow of the character described, a beam having a bifurcated standard provided

with a foot piece, a reversible share pivoted on the foot piece and having apertures, a hand lever fulcrummed on the beam and having a spur engaging an aperture in the reversible share, and a coiled spring connecting the reversible share with the beam.

2. A plow including a beam having a bifurcated standard provided with a foot piece, a reversible share having right and left hand mold boards provided with apertures, a pivot member whereby the reversible share is mounted on the foot piece, the apertures in the share being at opposite sides of and equidistant from the axis of the pivot member, an attaching member extending rearwardly from the convergence of the mold boards in substantially parallel relation to the axis of the pivot member, a spring connecting the attaching member with the beam adjacent to the rear end of the latter, a hand lever fulcrummed on the beam and having a spur guided between the side members of the bifurcated standard and engaging an aperture in the share, and an actuating spring for said hand lever.

In testimony whereof I affix my signature in presence of two witnesses.

DAVID COCHRAN.
